DESIGN FOR A COAT

Charles Leibowitz, New York, N. Y.

Application February 1, 1941, Serial No. 98,634

Term of patent 3½ years

To all whom it may concern:

Be it known that I, Charles Leibowitz, a citizen of the United States of America, residing in New York city, county of New York, and State of New York, have invented a new, original, and ornamental Design for a Coat, of which the following is a specification, reference being had to the accompanying drawing, forming part thereof or wherein.

Figure 1 is a front view of a coat showing my new design.

Figure 2 is a rear view of the coat shown in Figure 1.

The characteristic feature of my design resides in the combination on the full skirted coat disclosed of the specific stitching on the sleeves, in association with the seamed back, all as shown.

I claim:

The ornamental design for a coat, substantially as shown and described.

CHARLES LEIBOWITZ.
